UNITED STATES PATENT OFFICE.

HARRY E. MORTON, OF BOSTON, MASSACHUSETTS.

VACUUM-BREAKER.

1,266,976.

Specification of Letters Patent. Patented May 21, 1918.

Application filed May 10, 1916. Serial No. 96,613.

To all whom it may concern:

Be it known that I, HARRY E. MORTON, a citizen of the United States, residing at Boston, in the county of Suffolk and State 5 of Massachusetts, have invented an Improvement in Vacuum-Breakers, of which the following is a specification.

This invention relates to vacuum-breakers adapted to open the vacuum space of a jet 10 condenser to the atmosphere, and thereby destroy the vacuum between the said condenser and the engine in case the condensing water rises abnormally in the condenser, thereby to check its progress, and prevent 15 it from flowing back through the exhaust steam-pipe to the engine and wrecking the engine.

The invention is intended as an improvement on the vacuum-breaker of my Patent 20 No. 1,204,302, dated November 7th, 1916, and involves the same principle of operation, in that the weight of the condensing water is utilized to cause the operation of the air inlet valve to open the vacuum space 25 to the atmosphere, and destroy the vacuum.

The vacuum-breaker of my aforesaid application involves a receptacle which is arranged at the outside of the condenser and is closed to the atmosphere, and is in open 30 communication with the interior of the condenser to receive the condensing water which rises therein to an abnormal level, and which would flow back through the exhaust steam-pipe to the engine unless its 35 progress was checked, said receptacle being movable by the weight of the condensing water to operate suitable means for opening an air inlet-valve to open the vacuum space to the atmosphere, and thereby destroy the 40 vacuum, and thus check the progress of the condensing water and prevent it from flowing back through the exhaust steam-pipe to the engine.

The present invention involves improvements in the construction of the supporting-frame for the component parts, and of the counterbalancing means for the receptacle; also improvements in the construction 45 of the tripping-mechanism for the actuating-lever of the air-inlet valve; also the provision of means whereby the valve actuating-lever may be employed as an actuator to reset the tripping-mechanism, and also to restore the receptacle to normal position;

also in other details, as will be hereinafter 55 set forth.

Figure 1 is a side elevation of a vacuum-breaker embodying this invention which is adapted to be associated with a jet-condenser, the parts being in their normal or 60 set position.

Fig. 2 is a front elevation of the same.

Fig. 3 is a view similar to Fig. 1, the parts 65 having been released to open the vacuum space to the atmosphere.

Fig. 4 is a vertical sectional detail of the hollow supporting frame.

Fig. 5 is a sectional detail of the means 70 arranged between the arm bearing the counterweight and the receptacle.

Fig. 6 is a fragmentary detail.

Fig. 7 is a small conventional view of the jet-condenser with vacuum-breaker attached to its side wall.

The vacuum-breaker here shown is adapt- 75 ed to be applied exteriorly to the side of a condenser, but its application is not limited to this particular part of the vacuum space. In applying it to a jet condenser, the shell or case 12 of the condenser, see Fig. 2, has 80 an opening at the side, above the normal level of the condensing water, and over said opening, there is extended a frame 20, which is bolted to the shell, and, said frame, as here shown, serves as a support for the component parts of the vacuum-breaker. That portion of the frame which engages the shell 85 has a hole 21 through it, see Fig. 4, opposite the hole in the shell; and also has an upward extension 22, which is made hollow 90 and arranged for open communication through said hole 21, with the vacuum space of the condenser. Said hollow extension 22 has an opening at the top, to the atmosphere, which opening is formed with a valve-seat 95 23, adapted to receive any usual or suitable valve 24, designed to be opened outwardly and to be operated by means exteriorly disposed with respect to the condenser, thereby to open the vacuum space to the atmosphere and destroy the vacuum. Said valve 24 has a stem 25 which extends upwardly through a hole in the bracket 26, arranged on the frame, thereby to hold it in upright position and guide its vertical 100 movements, and a weight is preferably arranged on said stem. The stem 25 has a hole 27 through it transversely to receive

105

one end of an actuating-lever 28, which is pivoted at 29, to the bracket 26. The other end of said lever bears a heavy weight 30, which is designed, when permitted to fall by gravity, to move said lever on its pivot to positively lift said valve from its seat, thereby to open the vacuum space to the atmosphere. Normally said actuating-lever is held in position with its weighted end 10 portion elevated and in readiness to fall when permitted, by a suitable tripping-mechanism which is controlled by an operating-device, which latter is adapted to be operated by the weight of the condensing-water rising abnormally in the condenser.

The operating-device, as here shown, consists of a hollow receptacle 35, arranged in open communication with the vacuum space, but closed to the atmosphere, it having a 20 hollow or tubular neck 36 at one end, preferably bent at right angles to the body-portion to form an elbow, the end-portion 37, of which has a conical terminal 38, adapted for rotary engagement with a correspondingly shaped seat 39, formed around the edge of the opening 21, in the frame 20 to provide a tight bearing or support at such place. Said neck 36 has a trunnion 40, arranged in alinement with its end-portion 37, and centrally disposed with respect thereto, which trunnion has its bearing in a bracket 41 on the frame. Said end-portion 37 is held in firm engagement with the seat 39, by a spring 42, see Fig. 6, arranged 25 on the trunnion 40, which acts expansively between the bracket 41 and the end-portion. To hold said spring 42 compressed on the trunnion, when the operating-device is removed from its bearing, a flanged collar 43 having a bayonet slot is arranged on the trunnion at the outer end of the spring 42, which may be thrust inward, against the force of the spring and into engagement with a pin 44, thereby to be locked in place. 40 An open bearing is provided in the bracket 41 for the trunnion, to enable it to be readily removed. To prevent the end-portion 37 being blown away from its seat, should the 45 vacuum be lost, a small bracket 100 is detachably secured to the bracket 41, which extends over the end and the top of the end-portion of the trunnion. The operating-device is thus pivotally supported on the frame, and is at all times in open communication with the vacuum space.

The pivotally supported operating-device is adapted to be oscillated about a horizontal axis and its end-portion 37 to move rotarily on its seat. 60 The receptacle 35 normally occupies a position slightly above the horizontal, so that condensation will not accumulate therein, as represented in Fig. 1, being held in such position by means hereinafter described, and in case the condensing-water

rises abnormally, such condensing-water will pass through the hole 21 in the supporting-frame and through the hollow neck and into the receptacle 35, and add its weight to the receptacle. 70

The receptacle is normally held in elevated position by a counterweight 45, arranged on one end of a lever 46, supported by lateral knife-edged pivots 47, which seat in V-notches formed in upright lugs 48, on a bracket 49, which is attached to or formed as a part of the supporting-frame 20. The other end of said lever, see Fig. 5, bears a conical stud 50 which engages in a conical socket formed in the bottom or end of the 80 head 51 of a pin 52. The pin 52 is loosely supported and is mounted for vertical reciprocation in a cage 53 which is attached to the end of the lever by its attaching-arms 54. The upper terminal of said pin 52 is of conical conformation and is seated for universal movement in a socket 55 formed in a boss 56, which is extended downwardly from the bottom of the receptacle 35. The boss 56 is made long enough 90 to provide against the disengagement of the pin 52, upon a lifting movement of the receptacle, except upon removal of the lever 46. The weight 45 acts to hold the receptacle 35, when empty, in elevated position, see 95 Fig. 1, and when so disposed the outer end of the lever 46 will engage the stop 101, but when the condensing-water enters the receptacle, said weight will be raised, as represented in Fig. 3. The downward swinging 100 movement of the receptacle 35 is limited by an upright stop-member or pin 58 which is supported at the outer end of the bracket 49.

Means are herein provided for lifting the counterweight 45, to overcome the balance 105 of the receptacle 35, thereby to cause said receptacle, when empty, to swing downward by its own weight. As here shown, said means comprises a lever pivoted at 60 to ears 61, on the stop 101, or the frame, 110 and a chain or cord 62, arranged to pass through a hole 63 in the outer end of one arm 64, of the lever which carries a weight 65, arranged below said arm, and a disk or button 66, arranged above said arm, said 115 chain or cord, when moved downward, causing the disk or button to engage the arm 64 of the lever and swing said arm downward, and correspondingly raise the other arm 67 of said lever. Said arm 67 is extended beneath the weight 45, and when raised will lift said weight, thereby permitting the receptacle to swing downward. The chain or cord 62 may be associated with any suitable 120 form of automatic engine stop-mechanism, not here shown, by which to move it and thereby effect a downward swinging movement of the receptacle to control the operation of the air-inlet valve, although it is 125 obvious, said chain or cord may be pulled 130

by hand, if desired. It is desirable to destroy the vacuum in order to shut down the engine quickly and the means thus provided accomplish this result.

- 5 The tripping-mechanism which is employed for controlling the actuator 28 of the air-inlet valve and which is engaged by the receptacle 35, comprises a lever 70, having a pivot-pin 71 at its upper end, which enters 10 a pivot-slot 72, in a vertical supporting arm 73, erected upon a bracket 74, which projects from the upper portion of the frame 20, said lever being thus free to swing and also to move vertically. Said lever has a 15 lateral extension 75, the upper end of which is arranged near the upper end of the lever, and forms a shoulder thereat for the engagement with a pin 76, which is extended laterally from the actuating-lever 28, and 20 said lever also has an angularly formed projection 77, above the shoulder, there being a recess between said projection and shoulder sufficient to receive the pin 76. The 25 actuating-lever when thus engaged is held from movement downward, although upon a swinging movement of said lever through a short arc in a direction toward the left, Fig. 1, the pin 76 will be disengaged. The lever 70 has a latch formed end-portion 30 80 adapted to engage a bevel-faced projection 81 arranged on top of the receptacle 35, when said receptacle is in its elevated position, as represented in Fig. 1, so that said lever is held by the receptacle in position 35 to engage the pin on the actuating-lever. When the receptacle is swung downward, the projection 81 thereon disengages the latch-formed end of the lever 70, permitting said lever to swing in a direction toward 40 the left, thereby to disengage the pin 76, whereupon the weighted actuating-lever falls and the air-inlet valve is opened. 45 A yielding stop-member 85 is arranged on the bracket 74, which is struck by the weighted actuating-lever, when the latter falls, see Fig. 3, thus limiting its downward movement. When the receptacle 35 is moved downward by the condensing-water entering it and has disengaged the tripping- 50 mechanism, and the tripping-mechanism has operated to disengage the actuating-lever 28, and the air-inlet valve has opened, the parts are in the position represented in Fig. 3. 55 It is herein designed that said parts shall be restored manually by a return movement of one of the elements only, and herein the weighted actuating-lever 28 is selected as the member to be operated to restore the 60 parts. Said member is adapted to be lifted from the position shown in Fig. 3, to the position shown in Fig. 1, and when so moved, the air-inlet valve is closed, and the pin 76 strikes the projection 77, and swings 65 the lever 70 back to its normal position and back into the condenser, and as the receptacle becomes empty, it should return to 70 normal automatically by the counterweight, and under usual conditions, this will be the case. But, in case it should fail for any reason, means are herein provided for positively lifting the receptacle by the hand 75 actuation of the lever 28, said means consisting of a finger 90, formed on the end of the lever 70, which is adapted to engage a hook-member 91, fixed to the top of the receptacle 35, and when said lever 70 is 80 moved by the engagement of the pin 76, with its projection 77, said projection 90 will engage said hook member and lift the receptacle. As the lever 70 is returned to normal, and the receptacle is or has been 85 lifted, the latch-formed end 80 of the lever will pass over the projection 81, in consequence of which the lever 70 will be moved longitudinally for this purpose by reason of its pivot-pin sliding in the pivot-slot in 90 the arm 70. Thus it will be observed that by merely lifting the weighted actuating-lever 28, all of the parts will be restored to normal. 95 Herein a pipe 95 is arranged for connection at one end with the hollow extension 22, of the frame 20, and at the other end with the exhaust steam-pipe 96 at a point above the condenser, as represented in Fig. 7, thus establishing open communication 100 therebetween. 105 On top of the extension 22 of the frame 20, a flange 98 is provided which surrounds the air-inlet valve, to form a cup which is adapted to be filled with a liquid to seal and also test the ground joint which forms the valve-seat. It will be noted that in case water of condensation enters the chamber of the hollow frame 20, at the top, it is free to pass through the passage at 22, and 110 return to the condenser, instead of accumulating therein. 115 I claim:— 1. A vacuum-breaker adapted for association with a jet-condenser, comprising a hollow supporting frame having an opening 120 through its engaging-portion by which communication with the vacuum-space is established, a conical bearing surrounding said opening, said frame having a hollow extension, an air-inlet valve arranged on said extension, a hollow receptacle pivotally connected with said frame which is closed to the atmosphere and has an opening arranged 125 opposite the opening in the frame, and a conical end-portion which rotarily engages the conical bearing, whereby open communication with the vacuum-space is established, and the receptacle is adapted to receive condensing-water which rises in the condenser. 130

said pin then enters the recess for engagement with the shoulder. The condensing-water contained in the receptacle will flow back into the condenser, and as the receptacle becomes empty, it should return to 70 normal automatically by the counterweight, and under usual conditions, this will be the case. But, in case it should fail for any reason, means are herein provided for positively lifting the receptacle by the hand 75 actuation of the lever 28, said means consisting of a finger 90, formed on the end of the lever 70, which is adapted to engage a hook-member 91, fixed to the top of the receptacle 35, and when said lever 70 is 80 moved by the engagement of the pin 76, with its projection 77, said projection 90 will engage said hook member and lift the receptacle. As the lever 70 is returned to normal, and the receptacle is or has been 85 lifted, the latch-formed end 80 of the lever will pass over the projection 81, in consequence of which the lever 70 will be moved longitudinally for this purpose by reason of its pivot-pin sliding in the pivot-slot in 90 the arm 70. Thus it will be observed that by merely lifting the weighted actuating-lever 28, all of the parts will be restored to normal.

Herein a pipe 95 is arranged for connection at one end with the hollow extension 22, of the frame 20, and at the other end with the exhaust steam-pipe 96 at a point above the condenser, as represented in Fig. 7, thus establishing open communication therebetween. 95 100

On top of the extension 22 of the frame 20, a flange 98 is provided which surrounds the air-inlet valve, to form a cup which is adapted to be filled with a liquid to seal 105 and also test the ground joint which forms the valve-seat. It will be noted that in case water of condensation enters the chamber of the hollow frame 20, at the top, it is free to pass through the passage at 22, and 110 return to the condenser, instead of accumulating therein.

I claim:—

1. A vacuum-breaker adapted for association with a jet-condenser, comprising a hollow supporting frame having an opening through its engaging-portion by which communication with the vacuum-space is established, a conical bearing surrounding said opening, said frame having a hollow extension, an air-inlet valve arranged on said extension, a hollow receptacle pivotally connected with said frame which is closed to the atmosphere and has an opening arranged opposite the opening in the frame, and a conical end-portion which rotarily engages the conical bearing, whereby open communication with the vacuum-space is established, and the receptacle is adapted to receive condensing-water which rises in the condenser 115 120 125 130

and to move downwardly by the weight of the condensing-water, and means controlled by said receptacle upon a downward movement thereof to control the operation of the 5 air-inlet valve.

2. A vacuum-breaker adapted to be arranged between a jet-condenser and the exhaust steam pipe of an engine, consisting of a hollow frame having an opening by which 10 communication with the vacuum space is established, a hollow receptacle pivotally connected with said frame which is closed to the atmosphere, and has an opening communicating with the interior of said frame, 15 to establish open communication with the vacuum space to receive condensing-water which rises in the condenser and to move downwardly by the weight of the condensing-water, said frame having a hollow extension with an opening communicating with the exhaust steam pipe, and an air-inlet valve arranged on said extension.

3. A vacuum-breaker adapted for association with a jet-condenser, comprising a hollow receptacle closed to the atmosphere, and in open communication with the vacuum space and adapted to be moved downward by the weight of the condensing-water which rises in the condenser and which enters it, 25 counterbalancing means for holding said receptacle, when empty, in elevated position, which is adapted to be overcome by the weight of the condensing-water and which is arranged to restore said receptacle to elevated position when the condensing-water 30 escapes, and an air inlet valve controlled by said receptacle upon a downward movement thereof.

4. A vacuum-breaker adapted for association with a jet-condenser, comprising a hollow receptacle closed to the atmosphere, and in open communication with the vacuum-space and rotarily seated to move downward by the weight of the condensing-water which 40 rises in the condenser, counterbalancing means for holding said receptacle in elevated position comprising a pivoted lever, a counterweight arranged on one end-portion thereof, the other end-portion having a projection, a loosely supported headed pin having a pointed end, the head of which pin is socketed to receive said projection, and a socketed boss arranged on the bottom of the receptacle in the socket of which said pointed end of the pin is received.

5. A vacuum-breaker adapted for association with a jet-condenser, comprising a hollow receptacle closed to the atmosphere, and in open communication with the 50 vacuum-space, and rotarily seated to move downward by the weight of the condensing-water which rises in the condenser, and counterbalancing means for holding said receptacle in elevated position, comprising a 55 pivoted lever, a counterweight arranged on

one end of said lever, and engaging-means on the other end of said lever arranged for engagement with the receptacle.

6. A vacuum-breaker adapted for association with a jet-condenser, comprising a hollow receptacle closed to the atmosphere, and in open communication with the vacuum-space, and rotarily seated to move downward by the weight of the condensing-water which rises in the condenser, counterbalancing means for holding said receptacle in elevated position, and means for lifting said counterbalancing means to permit downward movement of the receptacle.

7. A vacuum-breaker adapted for association with a jet-condenser, comprising a hollow receptacle closed to the atmosphere, and in open communication with the vacuum-space, and rotarily seated to move downward by the weight of the condensing-water which rises in the condenser, counterbalancing means for holding said receptacle in elevated position, a pivoted lever arranged for engaging the counterweight to lift it and permit downward movement of the receptacle, and means to move said lever on its pivot.

8. A vacuum-breaker adapted for association with a jet-condenser, comprising a hollow receptacle closed to the atmosphere, and in open communication with the vacuum-space to receive condensing-water which rises in the condenser and movable downwardly by the weight of the condensing-water, an air inlet-valve adapted to open the vacuum-space and destroy the vacuum, a weighted actuating-lever for said valve, and tripping-mechanism for said actuating-lever which is controlled by said receptacle, said tripping-mechanism comprising a pivoted lever having a shoulder to receive a pin on the actuating-lever, and having a projection above said shoulder, and having a latch-formed end for engagement with a projection on the receptacle.

9. A vacuum-breaker adapted for association with a jet-condenser comprising a hollow receptacle closed to the atmosphere, and in open communication with the vacuum-space to receive condensing-water which rises in the condenser and movable downwardly by the weight of the condensing-water, an air inlet valve adapted to open the vacuum-space and destroy the vacuum, a weighted actuating-lever for said valve, tripping-mechanism arranged for engagement with said actuating-lever and said receptacle, and means adapted to be operated by an upward movement of the actuating-lever for lifting the receptacle.

10. A vacuum-breaker adapted for association with a jet-condenser, comprising a hollow receptacle closed to the atmosphere, and in open communication with the vacuum-space to receive condensing-water

- which rises in the condenser and movable downwardly by the weight of the condensing-water, an air-inlet valve adapted to open the vacuum-space and destroy the vacuum, 5 a weighted actuating-lever for said valve, tripping-mechanism arranged for engagement with said actuating-lever and also said receptacle, whereby it is controlled by the receptacle upon a downward movement thereof 10 thereof, said tripping-mechanism including a pivoted lever having a projection at one end and a finger at the other end, said projection adapted to be engaged by the actuating-lever upon an upward movement thereof 15 to restore said lever and cause its finger to engage and lift the receptacle.
11. A vacuum-breaker adapted for association with a jet-condenser, comprising a hollow receptacle closed to the atmosphere, 20 and in open communication with the vacuum-space to receive condensing-water which rises in the condenser and movable downwardly by the weight of the condensing-water, an air-inlet valve adapted to open the 25 vacuum-space and destroy the vacuum, a weighted actuating-lever for said valve, tripping-mechanism for the actuating-lever which is controlled by the receptacle upon a downward movement thereof, and means associated with said tripping-mechanism arranged for engagement with the actuating-lever for resetting said tripping-mechanism upon an upward movement of said lever, and means associated with said tripping-mechanism and receptacle arranged for engagement upon an upward movement of the actuating-lever by which the receptacle is lifted. 30
12. A vacuum-breaker adapted for association with a jet-condenser, comprising a hollow receptacle closed to the atmosphere, 40 and in open communication with the vacuum-space to receive condensing-water which rises in the condenser and movable downwardly by the weight of the condensing-water, an air-inlet valve adapted to open the vacuum-space and destroy the vacuum, a weighted actuating-lever for said valve, tripping-mechanism for the actuating-lever which is controlled by the receptacle upon a 45 downward movement thereof, and means associated with said tripping-mechanism arranged for engagement with the actuating-lever for resetting said tripping-mechanism upon an upward movement of said lever. 50
13. A vacuum-breaker adapted for association with a jet-condenser, comprising a hollow receptacle closed to the atmosphere, 55
- and in open communication with the vacuum-space and adapted to be moved downward by the weight of the condensing-water 60 which enters it, means for holding said receptacle in elevated position and for restoring it to elevated position subsequently to a downward movement thereof, an air-inlet valve, actuating-mechanism and tripping-mechanism therefor, controlled by said receptacle upon a downward movement thereof, said valve, its actuating-mechanism, and tripping-mechanism being restored to normal upon movement of a component part 70 thereof.
14. A vacuum-breaker adapted for association with a jet-condenser, comprising a hollow supporting-frame having an opening through its engaging-portion by which communication with the vacuum-space is established, a valve-seat surrounding said opening, said frame having a hollow extension, an air-inlet valve arranged on said extension, a hollow receptacle closed to the atmosphere having an opening arranged opposite the opening in the frame, and having a valve-formed end-portion which engages the valve-seat, and a trunnion opposite said end-portion, to pivotally support said receptacle, a spring arranged on said trunnion for holding said valve-formed end-portion against its seat, and means engaging said spring for holding it on the trunnion when the receptacle is removed. 80
15. A vacuum-breaker adapted for association with a jet-condenser, comprising a hollow supporting-frame having an opening through its engaging-portion by which communication with the vacuum-space is established, a valve-seat surrounding said opening, said frame having a hollow extension, an air-inlet valve arranged on said extension, a hollow receptacle closed to the atmosphere, having an opening arranged opposite the 90 opening in the frame and having a valve-formed end-portion which engages the valve-seat, and a trunnion opposite said end-portion to pivotally support said receptacle, an open bearing for said trunnion, and a detachable member extending over the end and top of the trunnion for holding it in place. 95
- In testimony whereof, I have signed my name to this specification, in the presence of two subscribing witnesses.
